GOLF TARGET

George T. Brown, New York, N. Y.

Application December 23, 1930, Serial No. 504,363

1 Claim. (Cl. 265—20)

This invention relates to an apparatus designed primarily for use in practicing the golf swing, the primary object of the invention being to provide a practice net having means which when struck by a golf ball, will register the distance the ball would have traveled, if driven from the usual golf tee, over an open fairway.

An important object of the invention is to provide a device of this character which may be adjusted for use by golf professionals, or people having knowledge of distance driven when the golf ball is hit properly with a golf club.

A still further object of the invention is to construct an apparatus of this character which will be exceptionally sensitive in its operation, to the end that a sliced or hooked ball, which would strike the target a glancing blow, will move the registering device a shorter distance than if the target is struck squarely.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of an apparatus constructed in accordance with the invention, the forward portion thereof being broken away.

Figure 2 is a plan view of the apparatus.

Figure 3 is a rear elevational view thereof.

Figure 4 is a sectional view taken on line 4—4 of Figure 1.

Figure 5 is an enlarged fragmental sectional view through the head of the target.

Figure 6 is an elevational view of the register. Figure 7 is an enlarged fragmental sectional view through the upper portion of the apparatus, and illustrating the means for holding the body portion of the apparatus in its registering position.

Figure 8 is a fragmental elevational view illustrating the means for securing the sections of the head of the apparatus, within the front end of the body portion.

Referring to the drawings in detail, the device comprises a frame indicated generally by the reference character 5, which frame is supported by the leg members 6, as clearly shown by Figure 1 of the drawings. In order that the frame will be held against lateral movement while in use,

guy wires indicated by the reference character 7 are provided, the guy wires being formed with hooks 8 at their upper ends, which hook into eyes 9 that are secured to the upper portion of the frame, the lower ends of the guy wires being anchored in any suitable and well known manner. The frame 5 includes rectangular end sections 10, which are connected by means of the spaced longitudinal bars 11, which are shown as having their ends connected to the end sections 10. 10 Spaced bars 12 are also connected with the end sections 10, the bars being arranged in such spaced relation with respect to each other, to receive the rollers 13 which act as a support for the tubular body portion 14, to be hereinafter more fully described.

At opposite sides of the frame, are spaced bars 15, between which the rollers 16 are mounted, the rollers 16 acting to prevent lateral movement of the body portion 14, as it moves through the frame 5. The bars 15 as well as the bars 12 are connected at their ends, by means of blocks 16' that are mounted within the guide members 17 that in turn are secured to the inner surfaces of the side bars and upper and lower bars of the end sections 10, there being provided adjusting screws 18 and 19 respectively, operating on opposite sides of the blocks 16, for moving the blocks 16 and bars connected therewith, laterally, thereby adjusting the support for the body portion 14, in such a way that the action of the body portion will be exceptionally sensitive to the force of a golf ball directed to the head thereof.

As clearly shown by Figure 1 of the drawings, the tubular body portion 14 is of a length which is equal to approximately one-half the length of the frame, permitting of a wide range of movement of the body portion within the frame, so that golf balls driven various distances, may act upon the head and body portion, to register the distance in yards.

The head of the body portion comprises an inner portion 18' and an outer portion 19', the portions 18' and 19' being constructed of canvas, and of a diameter to closely fit within the body portion 14. The portions 18' and 19' are held in position by means of the retaining rings 20 and 21 which are spaced apart to provide a space for the reception of the padding material 22 that acts to deaden the rebound of the golf ball striking the head. Pins 23 are provided on the outer retaining ring 21 and move in bayonet slots formed in the forward end of the body portion 14, providing means whereby the head may be readily and easily disassembled. Brackets or stops 24 are se-

cured within the body portion 14, and provide means for securing the inner retaining ring in its proper position.

Secured along the upper edge of the body portion 14, is a rack bar 25 which is engaged by the pivoted arm 26 that has a finger 27 at its free end, so that when the body portion 14 has been moved longitudinally of the frame, the finger will move into engagement with the rack bar, to hold the body portion against return movement. An ear 28 extends upwardly from the arm 26 and is formed with an opening to receive one end of the cable 29, the opposite end of the cable being connected to the spring arm 30 which is mounted directly thereabove. Connected with the free end of the arm 30 is a cable 31 that moves over the pulley 32, the cable being of a length to extend to a point near the operator, so that the operator may by pulling the cable 31 cause the finger 27 and rack bar to become disengaged, thereby permitting the body portion 14 to return to its normal position at the front end of the frame.

The reference character 32 designates a cable that is connected to the body portion 14, through the medium of the pin 33 that extends upwardly therefrom, the pin being constructed to operate in the slot 34, formed in the bar 35, that extends longitudinally of the frame at the opposite side thereof. Connected with the pin 33 is a cable 32' that extends through screw eyes 37 arranged along the frame, in any suitable manner, the screw eyes acting as guides for the cable 32', to insure the true operation thereof. The opposite end of the cable 32 extends over the roller 38, from where it passes downwardly into the housing 39, that forms the body portion of the registering device, the body portion being supplied with graduations, and certain indicating characters to indicate distance by yards.

The front wall of the housing 39 is formed with a longitudinal slot through which a pin extends, the pin carrying laterally extended indicators 40, that move over the graduations.

Secured to one end of the cable 36, is a weight 41 which is sufficiently heavy to return the body portion 14 to its normal position when the finger 27 moves out of contact with the rack bar 25. It might be further stated that the housing 39 will of course be disposed near the tee from which a golf ball is being driven, so that the person driving the ball may determine at a glance the length of the drive.

Secured to the frame 5 and extending forwardly

from the front end thereof, is a circular hood 42 that tapers towards its forward end, defining an inclined lower surface 43 which is formed with an opening 44 through which the balls driven against the head of the device may fall. The forward end of the hood 42 is secured to the canvas strip 43' that acts as a net to confine the golf balls within certain bounds. An opening is formed in the canvas 43', so that golf balls driven towards the canvas 43', in the proper direction, will pass through the opening and engage the head of the body portion 14 to move the body portion.

In the use of the device, a person practicing driving stands directly in front of the opening in the canvas 43' and drives the golf balls towards the opening. A golf ball properly driven, will pass through the opening in the canvas and strike the head of the movable body portion 14, with such force as to move the body portion 14 rearwardly. As the body portion 14 moves rearwardly, the cable 32' is pulled, which in turn moves the indicators over the graduations of the housing 39, and since the finger 27 engages the rack bar, the indicators will be held in their registering positions, until the finger 27 is released, whereupon the weight 41, exerts a pull on the cable, returning the body portion 14 to its normal position.

While I have shown and described a weight for moving the body portion to its original position after being released, it is to be understood that by inclining the frame forwardly, the body portion will automatically return to its normal position by gravity, the weight acting to exert a pull on the cable to take up the slack thereon.

I claim:

In a device of the character described, a frame, roller members within the frame, a tubular body portion operating within the frame, and movable between the roller members, bars for supporting the roller members, guide members in which the ends of the bars are positioned, adjusting screws extending through the guide members at opposite sides thereof, and extending into the bars, said adjusting screws being adapted to move the roller members towards and away from the body portion, regulating the movements of the body portion, a head closing one end of the tubular member and adapted to be struck by a golf ball moving the body portion longitudinally of the frame and means for temporarily holding the body portion against return movement.

GEORGE T. BROWN.
